LIFE RAFT

Harold L. Kirby, Glendale, Calif., assignor, by direct and mesne assignments, to Helen V. Peez, Beverly Hills, Calif.

Application April 16, 1949, Serial No. 87,939

6 Claims. (Cl. 9—11)

1

This invention relates to buoyant person supporting devices for water sports such as swimming and bathing and for life-saving purposes and has for its principal object the provision of an improved form of raft, having a rigid buoyant frame and a non-rigid buoyant body portion supported by the frame and comprising a textile envelop of novel construction housing a plurality of removable, inflatable air-cells; thereby providing a construction which is light in weight and which (when the air-cells are deflated) may be packed within a small space.

Another object of the invention is to provide a raft having the above characteristics which is simple in construction, economical to manufacture and which is reliable in use.

Still another object of the invention is to provide a buoyant, person supporting float construction comprising a flexible casing containing a plurality of inflatable and removable air cells which are so constructed and arranged that, when inflated, the side walls of the air cells form reinforcing members which impart rigidity to the casing.

A still further object of the invention is to provide a buoyant, person supporting float construction comprising a flexible casing housing a plurality of removable and inflatable air cells which casing is so constructed and arranged that the closure means through which the cells are inserted or removed and the valve stem portions of the air cells are housed and protected against accidental damage or displacement.

Still another object of the invention is to provide a float construction having the above desirable characteristics and which includes means by which it may be attached to a frame structure.

With the above objects in view, together with such other objects and advantages as may subsequently appear, the invention resides in the parts, and in the construction, combination and arrangement of parts hereinafter described in the following specification of an exemplary mode of execution of the invention; reference being had to the accompanying drawings forming a part thereof, and in which drawings:

Fig. 1 is a top plan view of a raft embodying the invention; portions of the lacing being omitted and portions of the cell envelop or cover being shown pushed aside to show parts otherwise concealed.

Fig. 2 is an enlarged transverse section taken on the staggered line 2—2 of Fig. 1.

Figs. 3 and 4 are fragmentary sectional views taken on the lines 3—3 and 4—4, respectively of Fig. 1.

2

Fig. 5 is a perspective view of one of the air cells, and

Fig. 6 is a fragmentary bottom plan view of one end of the raft as viewed in Fig. 1 to show the method of securing the lacings together.

In the illustrated embodiment of the invention, the frame of the raft comprises a frame 1 of light weight tubing and forming a rectangle having rounded corners. Preferably, the frame is formed from a single length of tubing having the meeting ends welded together as at 2. By making the frame of light weight tubing such as aluminum, and of sufficient diameter, it is rendered buoyant and adds to the supporting capacity of the raft.

The float assembly of the raft comprises a cell envelop or cover 3 formed of heavy textile, such as canvas, and having side flanges 4, 4 comprising a top element 5 and a bottom element 6 sewed together by lines of stitching 7, 7. Slightly back from one end, the top and bottom elements 5 and 6 are connected together throughout their width by a narrow strip of fabric 8 stitched thereto at 9, 9 said strip having a series of openings 10 therethrough to receive the valve stem portions 11 of a series of air cells or bags 12 placed within and extending side by side longitudinally of the cover or envelop 3 as best shown in Fig. 1. The opposite ends of the cover portions 5 and 6 have sewed thereto at 13, 13 the opposite sides of a slide fastener 14, disposed a short distance back from the ends thereof by which the cells 12 may be enclosed within the cover.

The side flanges 4 are provided with a series of spaced lacing receiving grommets 15 and the corners of the top and bottom portions are united by corner lacing receiving grommets 16. The separated end flange portions at the slide fastener end of the cover 3 are provided with aligned, spaced pairs of grommets 17, 18, see Fig. 4, and at the opposite end the end flanges are secured together by grommets 19, positioned between the stems of the air cell valves 11 which protrude through the openings in the end strip 8; the flanges between said grommets being separable to permit access to the valves for inflating and deflating the cells.

The float assembly is secured within the frame by a lacing comprising a pair of lacing ropes 20 and 21 the ends of which are inserted through the center pair of grommets at one end of the float assembly as indicated in Fig. 6 and the other ends of the ropes are then wound in opposite spirals around the frame and through the successive grommets until they meet at the center pair of grommets at the opposite end of the

envelop after which they are tightened and adjusted to center the float assembly within the frame as shown in Fig. 1 and are then tied together in the manner shown in Fig. 6.

The cells 12 as here shown are formed of extruded rubber tubing which is then cut to length and the ends vulcanized or otherwise secured together as indicated at 22 and 23 with the valve stems 11 being inserted and sealed in one of the ends at that time. However, the cells may be formed in any other manner that is found economical considering production quantities, tooling costs and related matters; the only essential being that they be of elongated form of uniform cross section so that a plurality of cells may be placed side by side longitudinally of the float cover so that the adjacent side walls of the cells will be vertically disposed and will give rigidity to the float.

To remove a cell for replacement or repair, the cells are first at least partially deflated, the lacing at the slide fastener end of the envelop is released as shown in Fig. 1, the slide fastener opened and the cell or cells removed and replaced after which the end is closed by the slide fastener, the lacings are replaced and tied and the cells re-inflated.

The entire raft is light in weight and rides high in the water so that it can be readily pushed along by a swimmer. At the same time, the novel arrangement of the air cells makes a rigid structure of the float on which a person can be supported. Further, the spacing of the frame from the float assembly by means of the lacings makes the entire perimeter of the raft available for hand holds. Also when assembled and with the air cells deflated, the entire raft takes up little more room than that required for the frame itself. Still further it is to be noted that the end flanges of the float cover or envelop are separated to permit access to the cell valves and extend over them to protect the valves from injury and to protect the user from injury by the valves, and that, likewise, the end flanges at the opposite end of the envelop similarly protect the slide fastener and the user.

While the foregoing description includes the rigid frame member 1, it will be obvious that the float unit, per se, may be used without the frame since the novel form of air cell structure, upon inflation, causes the adjacent side walls of the cells to form vertically disposed reinforcing members (see Fig. 2) which will impart sufficient rigidity to the float to render it usable without the frame. In that form of use, the flanges are laced together at each end to enclose the valve stems and the slide fastener and, if desired, a lacing could also be applied to the grommets in the side flanges to make them more easily grasped by a user.

Also, while from a replacement standpoint it is preferable to form the air cells in separate units as shown in Fig. 5, it will be realized that for maximum manufacturing economy, the cell structure may be formed in single unit having two or more cells of the form here shown with the valves arranged to project through the end member of the casing in the same manner as shown in Fig. 3; the essential feature being that the cell structure comprise cells disposed in parallel and so shaped that when inflated, the adjacent sides of the cells will impart rigidity to the casing.

While in the foregoing specification I have described one embodiment of my invention, I do not

intend thereby to limit myself to the exact form disclosed and the invention includes all such modifications of the parts and of their equivalents and of the construction, combination and arrangement of such parts and equivalents as shall come within the purview of the appended claims.

I claim:

1. In a raft, a rigid, rectangular frame element formed of tubing and a float assembly mounted within the inner perimeter of said frame element and secured thereto by a lacing; said float assembly comprising a bag-like fabric casing of rectangular side outline and having flange portions extending along each side and each end thereof, 15 an end member extending across and closing one end of said casing adjacent the inner edge of the flange at that end of the casing and having a series of openings extending therethrough, a slide fastener extending across the other end of the casing adjacent the inner edge of the flange at that end of the casing, and a plurality of separate, inflatable air cells contained in said casing; each of said cells having a valve stem protruding through one of the openings in said end member to permit access thereto externally of said casing.

2. In a raft, a rigid, rectangular frame element formed of tubing and a float assembly mounted within the inner perimeter of said frame element 30 and secured thereto by a lacing; said float assembly comprising a bag-like fabric of rectangular side outline and having single flange portions extending along each side and a pair of parallel, superimposed flange portions extending 35 across each end thereof, an end member extending across and closing one end of said casing adjacent the inner edge of the flanges at that end of the casing and having a series of openings therethrough, a slide fastener closure means 40 extending across the other end of the casing adjacent the inner edge of the flanges at that end of the casing, and a plurality of separate inflatable air cells contained in said casing; each of said cells having a valve stem protruding through 45 one of the openings in said end member; each of said valve stems being of elongated, tubular configuration and having an air valve mounted in one end thereof.

3. In a raft, a rigid, rectangular frame element 50 formed of tubing and a float assembly mounted within the inner perimeter of said frame element and secured thereto by a lacing; said float assembly comprising a bag-like fabric of rectangular side outline and having single flange portions 55 extending along each side and pairs of spaced, parallel flanges extending across each end thereof, an end closure member extending across one end of said casing adjacent the inner edges of the pair of flanges at that end of the casing, a slide 60 fastener closure means extending across the other end of the casing adjacent the inner edges of the pair of flanges at that end of the casing, and a plurality of inflatable air cells contained in said casing; each of said cells having a valve 65 stem protruding through one of the openings in said end member; a series of grommets disposed in spaced relation along said flanges, and a lacing connecting said grommets with said frame element and maintaining said float assembly substantially centrally disposed within the inner perimeter of said frame element; said lacing serving additionally to bring said pairs of flanges together with resultant housing of said 70 slide fastener and the protruding portions of said 75 valve stems.

4. A person supporting float construction comprising a bag-like fabric casing of rectangular side outline and having single flange portions extending along each side and spaced, parallel flange portions extending across each end thereof, an end closure member extending across one end of said casing adjacent and parallel to the inner edges of the flange portions at that end of the casing, a slide fastener closure means extending across the other end of said casing disposed at the inner edge of the flange portions at said other end of the casing, and a plurality of elongated tubular air cells removably contained in said casing disposed in parallel relation to each other; the adjacent sides of said air cells, when inflated, combining to form vertically disposed reinforcing members effective to impart rigidity to the assembly.

5. A person supporting float construction comprising a bag-like fabric of rectangular side outline; said casing being formed of parallel plies of material secured together along their side edges by spaced parallel lines of stitching with resultant formation of side flange portions, an end closure member secured to one end of each of said plies back from the end edges thereof with resultant formation of said ends as a pair of separate, parallel end flanges; said end member having a series of openings therethrough, a slide fastener closure means secured to said plies at the opposite ends thereof and disposed back from said end edges with resultant formation of said other ends as a second pair of separate, parallel end flanges, and a plurality of elongated air cells removably mounted in said casing; each of said cells having a valve stem at one end thereof and each of said valve stems being disposed in one of the openings in said end member.

6. A person supporting float construction com-

prising a bag-like fabric casing of rectangular side outline and having a single flange portion extending along each side thereof and pairs of parallel flange portions along each end thereof, 5 an end closure member extending across one end of said casing adjacent the inner edges of the flanges at that end of the casing, a manually operable closure means extending across the opposite end of the casing adjacent the inner edges of the flanges at that end of the casing, a series of inflatable air cells removably mounted in said casing and having stem portions extending through said end closure member and terminating within the outer ends of the pair of 10 flanges adjacent said end closure member, a series of grommets in said side and end flanges, and a lacing disposed in said grommets; said lacing serving to secure the pairs of end flanges at each end together with resultant housing of said 15 stem portions and said manually operable closure means.
